United States Patent

Des. 238,090

Patented Dec. 16, 1975

238,090

PENDANT OR SIMILAR ARTICLE

Eugene A. Poulin, 85 Royal Oak Road,
New Britain, Conn. 06053

Continuation-in-part of abandoned design application Ser.
No. 344,472, Mar. 26, 1973. This application June 12,
1974, Ser. No. 478,642

Term of patent 14 years

Int. Cl. D11—01

U.S. CL. D45—17

FIG.1

FIG.2

FIG.3

FIG.4

FIG.5

FIG.6

FIG.7

FIG. 1 is a perspective view of a pendant or similar article showing my new design;

FIG. 2 is a front elevational view;

FIG. 3 is a rear elevational view;

FIG. 4 is a side elevational view of one side;

FIG. 5 is a side elevational view of the other side;

FIG. 6 is a top plan view; and

FIG. 7 is a bottom plan view.

This is a continuation-in-part of design application Ser. No. 344,472, filed Mar. 26, 1973 and now abandoned.

I claim:

The ornamental design for a pendant or similar article, as shown and described.
